CLAIM

The ornamental design for a ceiling fan, as shown and described.

DESCRIPTION

FIG. 1 is a top perspective view of a ceiling fan showing my new design;
 FIG. 2 is a bottom perspective view of the ceiling fan of FIG. 1;

FIG. 3 is a top view of the ceiling fan of FIG. 1;
 FIG. 4 is a bottom view of the ceiling fan of FIG. 1;
 FIG. 5 is a front view of the ceiling fan of FIG. 1;
 FIG. 6 is a rear view of the ceiling fan of FIG. 1;
 FIG. 7 is a left side view of the ceiling fan of FIG. 1; and,
 FIG. 8 is right side view of the ceiling fan of FIG. 1.
 Portions of the ceiling fan shown in broken lines form no part of the claimed design.
